Andrew Sonderfj.

UNITED STATES PATENT OFFICE.

ISAAC A. ROMMER, OF NEW YORK, N. Y.

DESIGN FOR A DOLL.

49,223.

Specification for Design. Patented June 20, 1916.

Application filed February 21, 1916. Serial No. 79,785. Term of patent 7 years.

To all whom it may concern:

Be it known that I, ISAAC A. ROMMER, a citizen of the United States, residing in the borough of Manhattan, county of Kings, and State of New York, have invented a new, original, and ornamental Design for Dolls, of which the following is a specification, reference being had to the accompanying drawing, forming part thereof.

The figure is a perspective view of the doll illustrating my new design.

I claim:

The ornamental design for a doll as shown.

Signed at borough of Brooklyn, city of New York, in the county of Kings and State of New York this third day of February A. D. 1916.

ISAAC A. ROMMER.

Witnesses:

C. S. ASHLEY,
HARRY J. NEUSCHAFER.
